(57) CLAIM

The ornamental design for a cookware side handle, as shown and described.

DESCRIPTION

FIG. 1 is a perspective view of the “cookware side handle”, showing my new design;

FIG. 2 is a right side elevation view thereof; the left side elevation view being the mirror image thereof;

FIG. 3 is a bottom plan view thereof;

FIG. 4 is a top plan view thereof;

FIG. 5 is a front elevation view thereof; and,

FIG. 6 is a back elevation view thereof.

The dot-dash lines in FIGS. 1 and 5 indicate a boundary of an internal portion that forms no part of the claimed design. The broken lines in FIGS. 1, 2, 5 and 6 are for the purpose of illustrating portions of the article that form no part of the claim.
